UNITED STATES PATENT OFFICE.

DONALD J. CAMPBELL, OF MUSKEGON, MICHIGAN.

ART OF MANUFACTURING PISTON-RINGS.

1,050,102.

Specification of Letters Patent. Patented Jan. 14, 1913.

Application filed March 7, 1912. Serial No. 682,304.

To all whom it may concern:

Be it known that I, DONALD J. CAMPBELL, a citizen of the United States of America, residing at Muskegon, in the county of Muskegon and State of Michigan, have invented certain new and useful Improvements in the Art of Manufacturing Piston-Rings; and I do hereby declare the following to be a full, clear, and exact description of the invention, such as will enable others skilled in the art to which it appertains to make and use the same.

My invention relates to improvements in the art of manufacturing piston rings and like devices.

The object of my invention is to provide means for producing a perfectly circular ring when finished and to provide an improved method of producing piston rings hereinafter more fully described and particularly pointed out in the claims.

Heretofore it has been customary to produce a ring of somewhat greater diameter than the bore of the cylinder in which it is to be operated then remove a portion of the ring at one side whereby the ring can be compressed into a less circumference or diameter and inserted in the cylinder, and by its resilience to yieldably engage the inner surface of the cylinder. This compressing of a normally circular ring distorts the same from a true circle and results in an imperfect fit in the cylinder. In attempting to obviate this difficulty it has also been tried to make the ring with its inner surface eccentric to its outer surface, the removed portion being taken from the thinnest part of the ring whereby the ring when compressed remains more nearly circular. This, however, is not entirely successful and is also objectionable for the reason that the plane opposite surfaces of the ring are greater at one side than at the other whereby it wears uneven and also leaves a clearance between the thin side of the ring and the bottom of the channel of the piston in which the ring is held.

My invention consists essentially of a novel method of manufacturing rings consisting of making a ring pattern of substantially the dimensions of the ring to be produced with the usual allowance for shrinkage and finishing and preferably concentric within and without; inserting in one side of this pattern a segment of substantially the extent of the portion of the ring to

be removed to provide for resilience and compression of the same; casting from this modified pattern; removing a portion of the casting substantially corresponding with the segment inserted in the pattern; compressing the casting to close the opening formed therein and while so compressed finishing the ring as preferred, as will more fully appear by reference to the accompanying drawings in which:

Figure 1 is a plan view of the pattern before being modified; Fig. 2 the same of the pattern cut through at one side without removing any material portion thereof and expanded to the desired extent the broken lines illustrating the change of form; Fig. 3 the same with the segment inserted; Fig. 4 a plan view of a casting made from the modified pattern; Fig. 5 a plan view of the casting with the portion removed corresponding to the segment inserted in the pattern; and Fig. 6 the casting compressed to close the opening after the said portion has been removed.

Like numbers refer to like parts in all of the figures.

1 represents a plan of the original pattern; 2 the opening therein after the same has been severed and expanded to receive the segment; 3 the segment inserted in the pattern; 4 represents a casting made from said pattern; 5 represents the opening formed therein by removal of a portion corresponding to the inserted portion 3 in the pattern, which opening in Fig. 6 is shown closed by compressing the casting to the same extent that the pattern was expanded.

It will be noted that when the pattern is severed at one side and expanded to receive the segment it is thrown out of a true circle more or less according to the amount of expansion and that when the segment 3 is inserted it is held in this distorted condition for the purpose of making the casting which will correspond precisely to the amount of distortion of the original pattern. It is also obvious that when one side of this distorted casting is removed corresponding to the portion represented in the pattern by the inserted segment that the remainder of the ring will be normally distorted to the same extent as the original pattern was and the casting will obviously be restored in a true circle when compressed to the same extent that the pattern was expanded and thus be a perfect fit within the

cylinder, it being understood that material having uniform resilience throughout is used in the pattern and the casting, the distortion of the pattern before casting being neutralized by the restoration of the casting to the condition of the pattern before being distorted by insertion of the segment.

No very smooth finish being necessary upon the inner surface of the ring I find a satisfactory fit of the ring to the bottom of the groove in the piston is had by leaving the ring unfinished on the inner surface. Leaving the "skin" of the casting improves the resilience and strength of the ring. The remaining surfaces are finished in the usual manner while the casting is compressed as above described.

What I claim is:

1. The art of making piston rings and the like, comprising inserting a segment in a circular pattern whereby the pattern is distorted from a true circular form, casting from said pattern, removing from said casting a portion substantially corresponding to the inserted segment in the pattern, compressing the casting to close the opening

therein, and finishing the casting to the working size while in the said compressed condition.

2. The art of making piston rings and the like, comprising forming a pattern to the working size and shape of the proposed ring with only shrinkage and finishing material added; inserting a segment in said pattern to expand and distort the pattern out of a true circular form, casting from said pattern a ring distorted to correspond to the distortion of the pattern; removing from the casting a portion substantially corresponding to the segment inserted in the pattern, compressing the casting to close the opening formed by said removal and to remove the distortion therefrom, and finishing the ring to the working size and shape while thus compressed.

In testimony whereof I affix my signature in presence of two witnesses.

DONALD J. CAMPBELL.
